NURSER NIPPLE

Raymond W. Barton and Glen A. Claybaugh, Evansville, Ind., assignors to Mead Johnson & Company, a corporation of Indiana

Filed Dec. 10, 1968, Ser. No. 14,872

Term of patent 14 years

Int. Cl. D24—05

U.S. Cl. D83—8

FIGURE 1 is a side elevation view of a nurser nipple embodying our new design;

FIGURE 2 is a side elevation view, looking to the left in FIGURE 1;

FIGURE 3 is a top plan view looking down from the top of FIGURE 2; and

FIGURE 4 is a bottom plan view looking up from the bottom of FIGURE 2.

The side opposite FIGURE 1 is identical to that shown.

The side opposite FIGURE 2 is identical to that shown.

We claim:

The ornamental design for a nurser nipple, as shown and described.
